SUPPORT FOR A TELEPHONE HAND SET AND MEMO PAD

Richard J. McFadyen, Upper Montclair, N.J., assignor to Ketcham and McDougall, Inc., Roseland, N.J., a corporation of New Jersey

Filed Oct. 19, 1961, Ser. No. 67,152

Term of patent 14 years

(Cl. D74—1)

FIG. 1

I claim:

The ornamental design for a support for a telephone hand set and memo pad as shown.
